(57) **CLAIM**

I claim the ornamental design for a base of fuel injector puller, as shown and described.

DESCRIPTION

FIG. 1 is a top, front, right perspective view of a base of fuel injector puller showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof;

FIG. 8 is a top, front, right perspective view showing the base of fuel injector puller in use; and,

FIG. 9 is a partially cross-sectional view of FIG. 8.

The broken lines in the drawings illustrate portions of the base of fuel injector puller which form no part of the claimed design.

The broken lines rendered in FIGS. 8 and 9 illustrate the environment of the claimed design and form no part thereof.
